(57) **CLAIM**

The ornamental design for a self-leveling tile spacer, as shown and described.

DESCRIPTION

FIG. 1 is a top front right perspective view of the self-leveling tile spacer showing the new design;

FIG. 2 is a front elevational view of the self-leveling tile spacer thereof;

FIG. 3 is a rear elevational view of the self-leveling tile spacer thereof;

FIG. 4 is a left side elevational view of the self-leveling tile spacer thereof;

FIG. 5 is a right side elevational view of the self-leveling tile spacer thereof;

FIG. 6 is a top plan view of the self-leveling tile spacer thereof;

FIG. 7 is a bottom plan view of the self-leveling tile spacer thereof; and,

FIG. 8 is an exploded top right perspective view of the self-leveling tile spacer thereof;

FIG. 9 is an alternate position of the top right perspective view of the self-leveling tile spacer thereof; and,

FIG. 10 is an alternate position of the top right perspective view of the self-leveling tile spacer thereof.
